UNITED STATES PATENT OFFICE.

PETER TOTH, OF VINTONDALE, PENNSYLVANIA.

LOCK.

982,696.

Specification of Letters Patent. Patented Jan. 24, 1911.

Application filed October 12, 1910. Serial No. 586,724.

To all whom it may concern:

Be it known that I, PETER TOTH, a subject of the King of Hungary, residing at Vintondale, in the county of Cambria and State of Pennsylvania, have invented certain new and useful Improvements in Locks, of which the following is a specification, reference being had therein to the accompanying drawing.

10 This invention relates to locks, and the objects of the invention are to furnish a lock with a bolt that requires two keys to shift the same, and to provide a double key lock that cannot be very readily opened except by a person familiar with the same.

I attain the above objects by a mechanical construction that will be hereinafter specifically described and then claimed, and reference will now be had to the drawing forming a part of this specification, where-

in:—

Figure 1 is an elevation of the lock with the front plate thereof removed, Fig. 2 is a rear elevation of the lock, Fig. 3 is a vertical sectional view of the same, Fig. 4 is a bottom plan of a portion of the locking bolt, and Figs. 5 and 6 are perspective views of keys employed for manipulating the lock.

The lock comprises a rectangular casing 30 having a front plate 1, a rear plate 2, top and bottom walls 3 and side walls 4 and 5. The rear plate 2 is connected to the front plate 1 by screws 6 or other fastening means.

The side wall 5 has an opening 7 to accommodate the outer end of a locking bolt 8, the opposite end of said bolt is simply mounted in a bracket 9, carried by the front plate 1 adjacent to the side wall 4. The locking bolt 8 is rectangular in cross section 40 and the lower side thereof adjacent to the outer end is provided with two sets of teeth 10 and 11, the teeth 10 being arranged at one edge of said bolt and the teeth 11 at the opposite edge, with said teeth the reverse of 45 the teeth 10. The upper side of the bolt 8 intermediate the ends thereof is provided with a transverse slot 12.

The top and bottom walls 3 are connected by a guide 13 and arranged in parallelism 50 with this guide is another guide 14 of a less length than the guide 13. These guides are provided with alining openings 15 for the bolt 8, and slidably mounted between said guides and against the rear plate 2 is a

latch 16 having one side thereof cut away 55 to provide a recess 17 through which the bolt 8 extends. The lower end of the latch 16 is beveled, as at 18 and interposed between the upper end of said latch and the top wall 3 is a coiled compression spring 19 60 adapted to normally hold the upper wall of the recess 17 of the latch in the transverse slot 12 of the bolt 8.

The rear plate 2 is provided with an inverted keyhole 20 in which is placed the 65 shank 21 of a key 22, said shank having radially disposed teeth 23 and 24, these teeth being beveled in opposite directions to engage the teeth 10 and 11 and shift the bolt 8. The rear plate 2 is provided with another 70 keyhole 25 in which is placed the shank 26 of a key 27, said shank having a radially disposed lug 28, which is recessed at the end thereof, as at 29 to engage the lower beveled end of the latch 16. The key 27 must be 75 used first to elevate the latch 16 before the key 22 can be turned to move the bolt 8 in either direction.

From the foregoing it is apparent that I have devised a simple and inexpensive lock 80 that requires two specially constructed keys to manipulate the same, and while in the drawing there is illustrated a preferred embodiment of the invention, it is to be understood that the structural elements thereof 85 are susceptible to such changes as fall within the scope of the appended claim.

What I claim is:—

A lock comprising a casing, a locking bolt slidably mounted therein and having 90 the lower side thereof provided with two rows of reversely arranged teeth, a key adapted to be inserted in said casing to engage said teeth and shift said bolt, a latch 95 slidably mounted in said casing and adapted to engage the outer side of said bolt and hold said latch, a key adapted to be inserted in said casing to engage the lower end of said latch and elevate the same to release said bolt, and means arranged in said casing 100 and adapted to normally hold said latch in engagement with said bolt.

In testimony whereof I affix my signature in the presence of two witnesses.

PETER TOTH.
